UNITED STATES PATENT OFFICE.

GEORGE S. CONGER, OF NEW YORK, N. Y., ASSIGNOR TO DOW, JONES & COMPANY, OF NEW YORK, N. Y.

PRINTING-TELEGRAPH RECEIVERS

1,178,215.

Specification of Letters Patent.

Patented Apr. 4, 1916.

Application filed October 18, 1911. Serial No. 655,350.

To all whom it may concern:

Be it known that I, GEORGE S. CONGER, a citizen of the United States, residing at New York city, New York, have invented 5 certain new and useful Improvements in Printing-Telegraph Receivers, of which the following is a clear, full, and exact description.

This invention relates to a printing-telegraph receiving apparatus which is adapted to receive electrical messages and present the same upon a printed page, and is of the general character as shown in the patent to Landfear #765,978, dated July 26, 1904. 10 As is usual in such machines, my apparatus is arranged to be controlled by a transmitting circuit and comprises the several features of means for holding a sheet of paper, a rotatable type-wheel, and means for moving 15 said type-wheel and paper sheet transversely of one another for letter-spacing, together with means for feeding the paper longitudinally of said type-wheel for line-spacing.

More particularly the present improvement consists in providing an individual source of power for actuating each one of the above-named mechanisms of the apparatus and in having each one of said actuators under the immediate control of the transmitting circuit for positively operating their respective mechanisms, whereby all of the operating parts of the machine are made quickly responsive to the messages sent. By 20 this arrangement, a suitable construction of which will be described at length in the following specification, I have provided a printing telegraph-receiver which will operate at a much higher rate of speed and 25 with far greater accuracy in presenting messages, than the machines at present in use.

My invention consists further in several improved details of construction as will be 30 hereinafter described, as well as the general combination of parts making up the complete machine, and I am aware that many modifications and equivalent arrangements may be employed without departing from 35 the full scope of my invention.

In the drawings which show the preferred embodiment of my invention, Figure 1 is a front elevation of the entire machine; Fig. 2 is a sectional plan of the same through 40 line 2-2 of Fig. 1; Fig. 3 is a left-hand end

view of the machine; Fig. 4 is a right-hand end view; Fig. 5 is a transverse section along line 5-5 of Fig. 1 looking in the direction of the arrow; Fig. 6 is a transverse section along line 6-6 of Fig. 1 looking in the direction of the arrow; Fig. 7 is a sectional detail of the type-wheel; Figs. 8 and 8^a are further sectional details of said type-wheel through line 8-8 and 8^a-8^a respectively of Fig. 7; Fig. 9 is a detail of the feeding rack; Fig. 10 is a sectional detail of one end of the type-wheel shaft showing tension means thereon; Fig. 11 is a sectional detail of the circuit-closer for the winding circuit; Fig. 12 is an end view of said circuit-closer; Fig. 13 is a detail of the paper-feeding pawl mechanism; Fig. 14 is a detail perspective of the type-wheel guard; Fig. 15 is a diagrammatic view of the electro-magnetic actuators for the different parts of the machine, together with the energizing circuits therefor; and Fig. 16 is a detail section through line 16-16 of Fig. 10 showing a contour of the torsion spring for the type-wheel shaft.

Referring more particularly to the drawings, the frame of the receiving instrument consists of the base 1 and end plates 2 and 3. Mounted in suitable bearings in the upper portion of the end plates is the type-wheel shaft 4 carrying a type-wheel 5 keyed thereto for rotation therewith but slidably mounted on said shaft as shown so as to be moved transversely back and forth along the same. The type-wheel 5 is preferably of the usual construction having fixed to its periphery the characters to be printed, and the particular manner preferred by me for mounting this type-wheel 5 on its shaft 4 so as to be freely slidable thereon and yet preserve a definite and fixed printing point for each one of its characters is shown in Figs. 7, 8 and 8^a. Referring to said figures it will be seen that the type-wheel has adjacent to its hub 22 a separate collar or follower 24 connected to said hub 22 by a coil spring 26 tending to rotate said type-wheel and collar in opposite directions relative to said shaft 4. The type-wheel in its keyed connection to the shaft 4 has a slot 25 slightly wider than its feather 25' so that there is a loose play in said connection (see Fig 8^a). Also the follower 24 in its keyed connection is provided with a slot 23 wider than the feather 25',

whereby it also has a free play on the shaft 4. Since the type-wheel hub 22 is connected to the follower 24 by coil spring 26, it will be obvious that the separable parts are thus held against the opposite sides of their respective slots 23 and 25 so as to maintain a fixed relation to the shaft 4 and yet permit of an easy sliding movement thereon, due to the wide slots.

- 10 The type-wheel shaft 4 is provided with the usual escapement mechanism at one end thereof for controlling its rotation, shown more particularly in Figs. 1 and 4. This escapement mechanism comprises an escape wheel 7 fixed to the shaft 4 and released step by step by the double hooked arm 8, which forms the armature of polarized magnets W. In the present embodiment these polarized magnets are operated in the 15 usual manner by the transmitting circuit 96 as shown in Fig. 15, which transmitting circuit may have an alternating current passing therethrough whose number of alternate impulses for fixing the type-wheel shaft in different positions is controlled by a transmitter (not shown). The means for sending alternate impulses through said transmitting circuit is indicated diagrammatically in Fig. 15 by the circuit 20 changer 99'.

Type-wheel shaft actuating mechanism.—The means for creating a constant tension on the type-wheel shaft 4 tending to rotate the same consist of a coiled spring 6 (see 25 Figs. 1 and 10), connected at one end to the shaft 4 through escape pinion 7, and at its other end to a pinion 57 loosely mounted on said shaft 4, as shown in Fig. 30 10. The torsion spring 6 is kept in a wound condition tending at all times to rotate the shaft 4 by means of a large spur gear 58 (see Figs. 1 and 4) engaging with the pinion 57, said gear 58 being intermittently driven in the same direction by a pawl-carrier 62 loosely mounted on shaft 60 and having a pawl 61 for engaging a ratchet wheel 59 connected to said spur gear 58. A spring 63 tends to keep the pawl 61 in 35 engagement with said ratchet 59, and the pawl-carrier 62 is oscillated by means of an arm 64 fixed to shaft 65, said shaft also having fixed thereon an armature 66 which is attracted by the magnet Z which forms 40 the source of power or the electro-magnetic actuator for the type-wheel shaft winding mechanism (see Fig. 2). A spring 67 moves the arm 64 for withdrawing the armature 66, and a stop 68 is provided to limit said 45 movement. Spring detent 61^a prevents retrograde rotation of spur gear 58.

The electro-magnetic actuator Z is energized intermittently by a circuit 103, 104, shown diagrammatically in Fig. 15. An 50 intermittent circuit-closer 100 for closing

this winding circuit with the necessary frequency is mounted on one end of the type-wheel shaft 4, as shown in Fig. 3. Said circuit-closer comprises the conducting portion 101 and an insulating brake 102, upon which 70 bear brushes 101', 102', respectively, connected in said circuit 103. The winding circuit receives its current from any suitable source, such as battery B shown in Fig. 15, and it will be clear that at each rotation of the type-wheel shaft 4 the circuit is closed by the circuit-closer 100 to energize magnet Z and consequently wind up spring 6. The arrangement is such that the spring is wound up at each rotation of the shaft at 75 least as much as it loses by said rotation, so that the tension upon the same is substantially constant, although preferably the battery B should be of such strength as to be ineffectual for operating the armature 66 80 when said spring is wound tight. The coils of the torsion spring 6 surrounding shaft 4 are angular as shown in Fig. 16, instead of being circular, so that said spring when being wound by its pinion 57, will not buckle 85 and cramp. The coils are preferably shown as having been wound on a square arbor, although they might equally be wound on a five-sided, six-sided or seven-sided arbor, the essential requirement being that they 90 should not be circular. I have found that such a torsion spring may be used without the necessity of an outer covering shield for keeping it in place, for with angular coils as thus shown the spring will distribute its 95 tension throughout its length without buckling.

Letter-spacing mechanism.—For spacing letters in each horizontal line upon the printed page I prefer to move the type-wheel transversely of the sheet of paper, and for this purpose I mount a type-wheel carrier 27 slidably upon an angular shaft 28 as shown in Fig. 5. This type-wheel carrier is provided with forked arms 31 and 32 (see 105 Fig. 1) engaging grooved hub portions 33 and 34 at each side of the type-wheel 5, as shown in Figs. 1 and 7. The sides of the forked arms 31 and 32 are cut away as shown in Fig. 5, so as not to rest against the hub 110 of the type-wheel 5, thus avoiding any friction to prevent its free rotation, and the type-wheel carrier is further supported by a horizontal extension 29 running within a grooved rack 30 as shown in Fig. 5. This 115 construction provides a two-point slideable bearing for said type-wheel carrier to prevent any tendency of the same to rest against the type-wheel and check its free rotation. Upwardly extending arms 35 are also provided on the type-wheel carrier 27, and mounted in the ends of these arms is the usual ink-roller 36 adapted to bear against the type-wheel 5. Pivotally mounted at 120 40 upon a lower extension 39' of the type-wheel 125

carrier are pawls 37 and 38, which pawls are adapted to engage feed racks 41 and 42 for sliding said carrier 27 in one direction along its shaft 28. One of the feed racks, such as 41, is stationary, while 42 is caused to reciprocate by means of an armature lever 44 and pawl 43 engaging said rack as shown in Figs. 1 and 9. The armature 46 of said lever 44 is attracted by magnets Y which form the source of power or electro-magnetic actuator for operating the letter-spacing mechanism. The spring 111 is provided to return the lever 44 after each attraction, and a throw-off dog 45 is provided to disengage the pawl 43 from rack 42 after each forward movement to allow said rack to return under the force of a spring 56 connected thereto as shown in Fig. 2. An abutment 112 is also provided to limit the rearward movement of said lever 44. It will be obvious that at each forward movement of the feed rack 42 the type-wheel carrier 27 is carried a step along its support by the engagement of one of its pawls, such as 38, with the rack 42, and is maintained in its forward position by the engagement of the other pawl 37 with the stationary rack 41. Springs 73 and 72 as shown in Fig. 1 tend to keep the respective pawls 37 and 38 in engagement with the feed racks. In order to prevent any overthrow of the type-wheel carrier 27 under the forward impulse of said feed rack 42, a checking device is provided as shown more clearly in Figs. 1 and 9. This checking device preferably consists of a toothed bar 79^a supported on side arms 93^a fixed to a rocking shaft 93, which shaft is oscillated for operating the type-wheel return mechanism, as will be hereinafter described. The outside pawl 38 of the type-wheel carrier is provided with a lateral extension 38^a which, when said pawl rides upwardly over the teeth of the stationary rack 41, is thrown behind one of the teeth 79^b on the checking bar 79^a, as shown in Fig. 9. The teeth 79^b of the checking bar are located slightly forward of corresponding teeth on rack 41 and act to check the forward advance of the pawl 38 but permit it to drop into the notch of the next succeeding tooth on rack 42. Thus it will be seen that with the oscillation of lever 44 by the energization of magnet Y, the feed racks move the type-wheel carrier and type-wheel step by step transversely along their supports to the right of the machine, and by positively checking any overthrow, the type-wheel prints accurately and with even spacing between letters. A return arm 69 impelled by a spring 71 tends to return the carrier at all times to the left side of the machine.

The type-wheel is provided with a guard 56^a (as shown in Fig. 14) mounted on the carrier 27 (as shown in Fig. 5), which covers the type-wheel adjacent its print-

ing point, and has a transverse slot 57 for exposing the character to be printed. In order to prevent smearing of the printed characters on the paper as the type-wheel and guard is moved transversely thereof, the slot 57 of said guard is cut away at each end at 58 and 59 as shown in Fig. 14, whereby no part of the guard comes in contact with the page across the printed line.

Printing mechanism.—For impressing the paper against the type-wheel for printing after the same has been positioned, I have shown in the present embodiment a printing platen 53 extending transversely across the machine behind the sheet of paper and mounted on arms 52, in turn fixed to an oscillating shaft 51 (see Figs. 2, 5 and 6), said shaft 51 having a foot 50 extending outwardly therefrom and adapted to be engaged and oscillated by a cam wheel 49 rotatably mounted in the frame. The cam wheel 49 is provided with teeth adapted to be engaged by a pawl 48 carried on the moving feed rack 42 (see Fig. 9). By this construction it is seen that every time the feed rack 42 is returned by its spring 56, the cam wheel 49 is given a partial rotation and acts to depress foot 50 and consequently oscillate arms 52 and platen 53 against the paper for printing. This operation takes place preferably by the return movement of the feed rack 42, whereby the type-wheel is completely at rest ready for printing, having been moved to its new position by the forward movement of the feed rack 42. A spring such as 52' may be provided to keep the foot 50 in engagement with the cam wheel 49, and an adjustable stop 54 fixed at 55 may also be provided to limit the throw of foot 50 under the action of said cam wheel.

The circuit for energizing the magnet Y and consequently operating the letter-spacing mechanism and the printing mechanism through armature 46 is shown diagrammatically at 97 and 98 in Fig. 15. This letter-spacing and printing circuit is connected to the battery B as shown, and is closed by an armature 99 attracted by relay magnet S in the transmitting circuit 96. It is understood that in machines of this character the alternate impulses of the transmitting circuit do not affect the relay magnet S, but when said transmitting circuit has fixed the type-wheel in its position for printing, the alternations cease and a current in one direction continues through said relay magnet S, thereby energizing the same and closing the relay circuit 97 and 98. It will thus be seen that the relay circuit 97 and 98 operating the magnet Y is promptly closed after the type-wheel has been fixed in position.

Line-spacing mechanism.—In order to space the lines of the printed matter on the

page, I preferably move the sheet of paper longitudinally of the type-wheel. The sheet of paper may be led from a let-off roll mounted in any convenient place adjacent to the machine (not shown) upwardly between the printing platen 53, type-wheel 5 and threaded between the paper feed rolls 16, 18, 17, 19 mounted at the upper portion of the machine as shown in Fig. 1. 5 The rolls 16 and 17 are carried on a common shaft 15, which shaft is journaled in the side plates 2 and 3 of the frame and rotated at proper times by a pawl and ratchet mechanism shown in detail in Figs. 5 and 10 13. The pressure rolls 18 and 19 are carried on swinging arms 20 and 21 respectively, so as to rest by gravity against the positively driven rolls 16 and 17 and adapted to be lifted therefrom when it is desired 15 to remove or thread the paper. At one end of the shaft 15 as shown in Figs. 1 and 5, is fixed a ratchet 74 having peripheral teeth 74' and pins 80 projecting from one side thereof as shown in Fig. 13. A pawl-carrier 20 78 is loosely mounted on the shaft 15 adjacent said ratchet 74, said carrier having a pawl 75 for engaging the teeth 74' of said ratchet. An operating arm 83 pivoted at 25 84 is connected by a link 79 with said pawl-carrier for swinging the same, and said arm 83 has an extension shoulder 84' for engaging with the pins 80 of said ratchet 74 when 30 said arm moves over to swing the pawl-carrier and operate the ratchet. This 35 shoulder 84' acts as a stop for preventing the overthrow of said ratchet wheel 74 when operated. The connecting link 79 is also provided with an extension hook 81 integral therewith, which normally rests just in 40 front of one of the pins 80 as shown in Fig. 13, when said ratchet wheel is at rest. This hook 81 prevents the ratchet wheel from being turned independently of the pawl-carrier in the direction of the arrow, as for 45 instance when one desires to feed the paper by hand and pulls the sheet through the rolls. It will thus be seen that the paper-feed shaft 15 is locked by shoulder 84' from an overthrow when said pawl-carrier is op- 50 erated and is held by the hook 81 from being turned when said pawl-carrier is at rest. It will also be understood that the hook 81 is so positioned that it will swing downwardly out of the way of pin 80 when 55 the pawl-carrier is moved in the direction of the arrow in Fig. 13. The operating arm 83 of the pawl and ratchet mechanism is oscillated by means of an armature lever 85 fixed to shaft 87 provided with armature 60 89 adapted to be attracted by the magnet X, which forms the source of power or electro-magnetic actuator for the line-spacing mechanism. A spring 86 is connected to armature lever 85 for withdrawing the 65 same.

Type-wheel return mechanism.—For ordinary purposes it is usually desirable to return the type-wheel at the left-hand side of the page for beginning a new line when the paper is fed forward to space said lines, and therefore I have connected with the line-spacing mechanism the mechanism for returning said type-wheel so that they will be operated simultaneously, although of course it is to be understood that they may be operated independently if desired. Extending forwardly from a shaft 93 mounted in the side plates 2 and 3 of the machine are arms 94 carrying at their outer ends the transversely-extending blade 95. Rearwardly extending from said shaft 93 is an arm 90 having a slot 91 engaging a pin 92 on the operating lever 83. The blade 95 is located beneath the projecting pin 40 of the pawl 38, whereby when the blade 95 is raised the pawl is withdrawn from engagement with rack 42. The pawl 38 has a lateral projection 37' as shown in Figs. 1 and 5, extending over the top of pawl 38, whereby when pawl 38 is raised it carries with it pawl 37 and thus releases both pawls from the racks 41 and 42 to allow the return of the type-wheel carrier 27 under the force of its return arm 69. It is thus evident that by each oscillation of the arm 83 the paper is fed forward for a new line and simultaneously the type-wheel carriage is released from the racks 41 and 42 and restored to its initial position relative to said paper sheet. Moreover, when the shaft 93 is rocked to release the pawls of the type-wheel carriage from the racks 41 and 42, the toothed checking bar 79' is also raised to withdraw its teeth completely from the path of movement of said extension 38' on pawl 38, said bar 79' being fixed upon the shaft 93, as hereinafter set forth.

The circuit for energizing the magnet X and thus operating the line-spacing and the type-wheel return mechanism is shown diagrammatically in Fig. 15 at 109 and 110 connected at opposite sides to the battery source B. This circuit is normally open at the break between contacts 107 and 108 and is closed when desired through the proper operation of the transmitting circuit by the following mechanism: Referring to Figs. 1 and 3, an arm 105' fixed to the armature 46 extends laterally through the side plate 3 of the machine and engages with a lever 105 pivoted at 105" on the plate 3. The lever 105 supports at its outer end a vertically extending support 106, which is made of two parts telescopically connected so as to yield in its lengthwise direction. Support 106 is guided in its vertical movement by slot 106' and pin 106" and carries pivoted to its upper end and insulated therefrom a contact 107 connected to one branch of the circuit 109. The contact 107 may have a small 115 120 125 130

spring for yieldingly keeping it in extended position upon the end of support 106. The type-wheel shaft 4 extends through the side plate 3 and carries at its outer end a disk 4' insulated therefrom. The disk 4' carries on its periphery a projecting contact pin 108 which is in electrical connection with the other branch 109 of said energizing circuit. It is understood that the lever 105 and contact 107 is vibrated vertically at each energization of magnet Y when a character is printed, and ordinarily the contact 108 is not in line with contact 107 for meeting the same in its upward movement and closing circuit 109, 110. Contact pin 108 is located on disk 4' at a point in its periphery corresponding to a blank space on the type-wheel, whereby when the type-wheel shaft is positioned for bringing 108 in line with 107, no character will be printed but the circuit 109, 110, will be closed by the upward movement of support 106 for energizing the actuator of the line-spacing and type-wheel return mechanism.

25 The present apparatus may be supplied with the synchronizing device of the well known character shown in Fig. 1, in which one end of the type-wheel shaft 4 is provided with a spiral groove 12 and pivotally mounted upon the frame adjacent said groove is a lateral swinging lever 13 having a pin 13' normally in engagement with the spiral groove 12. During the rotation of the shaft 4 the lever 13 by the engagement of its pin 13' with the spiral groove is adapted to swing laterally across the machine until a shoulder 13'' of the same comes in contact with the pin 14 of the type-wheel shaft 4, whereupon said type-wheel shaft is held from further rotation. The lateral travel of swinging lever 13 along groove 12 is sufficient to allow the type-wheel shaft 4 to rotate at least two full revolutions before shoulder 13'' comes in contact with the pin 14 for stopping said shaft 4. This allows the type-wheel to present any one of its characters to the printing point without danger of the shaft 4 being automatically stopped. During the operation of the machine this synchronizing lever 13 is disengaged from groove 12 at each actuation of magnet Y and is provided with a spring (not shown) for returning it to the left side of the machine. The swinging lever 13 is connected to the armature 105 of magnet Y by a rod 47.

60 Summary.—Referring to diagrammatic view, Fig. 15, the several operations of my receiving apparatus may be briefly summarized as follows: It is understood that a transmitter of any usual type (not shown) is connected in the transmitting circuit for sending alternate impulses of current through the circuit 96, the number of said impulses depending upon the character on

the type-wheel which it is desired to print, whereby the polarized escapement mechanism positions the type-wheel in its printing position. The last of the alternate impulses which fixes the type-wheel in its position continues through the circuit 96 in direct line for a sufficient length of time to energize the relay magnet S, closing the relay circuit 97 and 98, energizing magnet Y for operating the letter-spacing and printing mechanism as above described. When the operator at the transmitter reaches the end of a line he presses a key for positioning the type-wheel to bring contacts 108 and 107 in line, the circuit 109 and 110 being 70 then closed by causing the printing magnet Y to attract its armature 46. The actuator Z of the winding mechanism is energized by its circuit 103 and 104 independently of the other circuits by the contact closer 100 75 80 on the type-wheel shaft.

It will thus be plain that there is provided in the present apparatus a separate and individual actuator for the letter-spacing mechanism, line-spacing mechanism and the 90 type-wheel shaft tension mechanism, and that each one of these actuators is energized by an individual relay circuit under the control of the transmitting circuit 96, whereby each relay circuit may be quickly 95 responsive to the operation of said transmitting circuit for positively operating its respective actuator and corresponding mechanism.

What I claim is:

1. In a printing telegraph receiver in combination, a rotary type-wheel shaft carrying a type-wheel, an electro-magnetic actuator for automatically storing power to rotate said shaft, means for releasing said shaft, means for holding a sheet of paper and letter-spacing mechanism for shifting said type-wheel and said paper sheet transversely of one another, a second electro-magnetic actuator for operating said letter-spacing mechanism, line-spacing mechanism for shifting said paper longitudinally of said type-wheel, a third electro-magnetic actuator for operating said line-spacing mechanism, and an individual energizing circuit 110 115 for each of said above-named electro-magnetic actuators.

2. In a printing telegraph receiver in combination, a rotary type-wheel shaft carrying a type-wheel, an electro-magnetic actuator for automatically storing power to rotate said shaft, means for releasing said shaft, type-wheel positioning mechanism, means for holding a sheet of paper and letter-spacing mechanism for shifting said type-wheel and said paper sheet transversely of one another, a second electro-magnetic actuator for operating said letter-spacing mechanism, line-spacing mechanism for shifting said paper longitudinally of 120 125 130

said type-wheel, a third electro-magnetic actuator for operating said line-spacing mechanism, and an individual energizing relay circuit for each of said above-named 5 electro-magnetic actuators controlled by said type-wheel positioning mechanism.

3. In a printing telegraph receiver in combination, a type-wheel carrying a series 10 of type, type-wheel positioning mechanism comprising a transmitting circuit for determining the particular type to be printed, means for holding a sheet of paper and letter-spacing mechanism for shifting said type-wheel and paper sheet transversely of 15 one another, an electro-magnetic actuator for operating said letter-spacing mechanism, line-spacing mechanism for shifting said paper longitudinally of said type-wheel, a separate electro-magnetic actuator 20 for operating said line-spacing mechanism, an individual energizing relay circuit for each of said electro-magnetic actuators, including a source of electric energy therefor separate from said transmitting circuit, and 25 a relay magnet controlled by said transmitting circuit and operatively connected with said energizing relay circuits, with the armature of said relay magnet in the circuit of the electro-magnet of the letter-spacing 30 mechanism, whereby all of said parts are adapted to be moved by the energization of said relay magnet.

4. In a printing telegraph receiver in combination, a type-wheel carrying a series 35 of type, type-wheel positioning mechanism comprising a transmitting circuit for determining the particular type to be printed, means for holding a sheet of paper and printing mechanism for impressing said paper against said type wheel for printing, an electro-magnetic actuator for operating said printing mechanism, line-spacing mechanism for shifting said paper longitudinally of said type-wheel, a separate electro-magnetic 40 actuator for operating said line-spacing mechanism, and an individual energizing relay circuit for each of said electro-magnetic actuators, including a source of electric energy therefor separate from said 45 transmitting circuit, and a relay magnet controlled by said transmitting circuit and operatively connected with said energizing relay circuits, with the armature of said relay magnet in the circuit of the electro-magnet of the printing mechanism, whereby 50 all of said parts are adapted to be moved by the energization of said relay magnet.

5. In a printing telegraph receiver in combination, a type-wheel carrying a series 60 of type, type-wheel positioning mechanism comprising a transmitting circuit for determining the particular type to be printed, means for holding a sheet of paper and letter-spacing mechanism for shifting said 65 type-wheel and said paper sheet transversely

of one another, an electro-magnetic actuator for operating said letter-spacing mechanism, return-mechanism for restoring said type-wheel to its initial position relative to said paper sheet for a new line, an electro-magnetic actuator for operating said return-mechanism, and an individual energizing relay circuit for each of said electro-magnetic actuators controlled by said transmitting circuit. 75

6. In a printing telegraph receiver in combination, a rotary type-wheel shaft carrying a type-wheel, tension mechanism tending to rotate said shaft, an electro-magnetic actuator for said tension mechanism, 80 type-wheel positioning mechanism comprising a transmitting circuit for controlling the rotation of said shaft, means for holding a sheet of paper and letter-spacing mechanism for shifting said type-wheel and paper sheet transversely of one another, an electro-magnetic actuator for operating said letter-spacing mechanism, line-spacing mechanism for shifting said paper longitudinally of said type-wheel, an electro-magnetic actuator for 85 operating said line-spacing mechanism, and an individual energizing relay circuit for each of said electro-magnetic actuators controlled by said transmitting circuit. 90

7. In a printing telegraph receiver in 95 combination, a type-wheel carrying a series of type, type-wheel positioning mechanism comprising a transmitting circuit for determining the particular type to be printed, means for holding a sheet of paper and letter-spacing mechanism for shifting said type-wheel and paper sheet transversely of one another, printing mechanism for impressing said paper against said type-wheel for printing, a single electro-magnetic actuator for operating said letter-spacing mechanism and said printing mechanism, line-spacing mechanism for feeding said paper longitudinally of said type-wheel, a second electro-magnetic actuator for operating 100 said line-spacing mechanism, and an individual energizing relay circuit for each of said electro-magnetic actuators controlled by said transmitting circuit. 105

8. In a printing telegraph receiver in 115 combination, a type-wheel carrying a series of type, type-wheel positioning mechanism comprising a transmitting circuit for determining the particular type to be printed, means for holding a sheet of paper and letter-spacing mechanism for shifting said type-wheel and paper sheet transversely of one another, printing mechanism for impressing said paper against said type-wheel for printing, a single electro-magnetic actuator for operating said letter-spacing mechanism and said printing mechanism, line-spacing mechanism for shifting said paper longitudinally of said type-wheel, return 120 mechanism for restoring said type-wheel to 125 130

its initial position relative to said paper sheet for a new line, a second electro-magnetic actuator for operating said line-spacing mechanism and said return mechanism, 5 and an individual energizing relay circuit for each of said electro-magnetic actuators controlled by said transmitting circuit.

9. In a printing telegraph receiver in combination, a rotary type-wheel shaft carrying a type-wheel, an electro-magnetic actuator for giving rotation to said shaft, type-wheel positioning mechanism comprising a transmitting circuit for controlling the rotation of said shaft, means for holding a sheet of paper and letter-spacing mechanism for shifting said type-wheel and said paper sheet transversely of one another, printing mechanism for impressing said paper against said type-wheel for printing, a second electro-magnetic actuator for operating 10 said letter spacing mechanism and said printing mechanism, line-spacing mechanism for shifting said paper longitudinally of said type-wheel, return mechanism for restoring said type-wheel to its initial position relative to said paper-sheet for a new line, a third electro-magnetic actuator for operating said line-spacing mechanism and said return mechanism, and an individual energizing separately-closed relay circuit for 15 each of said electro-magnetic actuators controlled by said transmitting circuit.

10. In a printing telegraph receiver in combination, a rotary type-wheel shaft carrying a type-wheel, tension mechanism tending to rotate said shaft, an electro-magnetic actuator for said tension mechanism, an electro-magnetically-operated escapement for controlling the movement of said shaft, a transmitting circuit for said escapement, means for holding a sheet of paper and letter-spacing mechanism for shifting said type-wheel and paper sheet transversely of one another, printing mechanism for impressing said paper against said type-wheel for printing, a second electro-magnetic actuator for operating 20 said letter-spacing mechanism and said printing mechanism, an individual relay circuit for energizing said second electro-magnetic actuator adapted to be closed by a continuation of one of said transmitting impulses, line-spacing mechanism for shifting said paper longitudinally of said type-wheel, return mechanism for restoring said type-wheel to initial position relative to said paper sheet for a new line, a third electro-magnetic actuator for operating said line-spacing mechanism and said return mechanism, and an individual energizing relay circuit for each of said electro-magnetic actuators controlled by said transmitting circuit.

11. In a printing telegraph receiver in combination, a rotary type-wheel shaft carrying a type-wheel, an electro-magnetic actuator for creating a tension on shaft tending to rotate the same, an individual energizing circuit for said actuator adapted to be closed by each rotation of said shaft, an

escapement for said shaft comprising polarized magnets and armature, a transmitting circuit carrying alternating impulses for operating said polarized magnets, means for holding a sheet of paper and letter-spacing mechanism for shifting said type-wheel and paper sheet transversely of one another, a second electro-magnetic actuator for operating said letter-spacing mechanism, an individual relay circuit for energizing said second electro-magnetic actuator adapted to be closed by a continuation of one of said transmitting impulses, line-spacing mechanism for shifting said paper longitudinally of said type-wheel, a third electro-magnetic actuator for operating said line-spacing, and an individual relay circuit for energizing said third electro-magnetic actuator adapted to be closed by the operation of said second actuator when the transmitting circuit has 85 fixed the type-wheel in a certain position.

12. In a printing telegraph receiver in combination, a rotary type-wheel shaft carrying a type-wheel, an electro-magnetic actuator for creating a tension on shaft tending to rotate the same, an individual energizing circuit for said actuator adapted to be closed by each rotation of said shaft, an escapement for said shaft comprising polarized magnets and armature, a transmitting circuit carrying alternate impulses for operating said polarized magnets, means for holding a sheet of paper and letter-spacing mechanism for shifting said type-wheel and paper sheet transversely of one another, printing mechanism for impressing said paper against said type-wheel for printing, a second electro-magnetic actuator for operating 90 said letter-spacing mechanism and said printing mechanism, an individual relay circuit for energizing said second electro-magnetic actuator adapted to be closed by a continuation of one of said transmitting impulses, line-spacing mechanism for shifting said paper longitudinally of said type-wheel, return mechanism for restoring said type-wheel to initial position relative to said paper sheet ready for a new line, a third electro-magnetic actuator for operating said line-spacing, and return mechanism, and an individual relay circuit for energizing said third electro-magnetic actuator adapted to be closed by the operation of said second actuator when the transmitting circuit has 95 fixed the type-wheel in a certain position.

13. In a printing telegraph receiver in combination, a rotary type-wheel shaft having a type-wheel slidably mounted thereon, means for holding a sheet of paper, a movable printing platen adapted to press said sheet against said type-wheel for printing, letter-spacing mechanism comprising a vibrating member adapted in one movement to shift said type-wheel along its shaft transversely of said paper sheet and in its re-

- turn movement to operate said printing platen.
14. In a printing telegraph receiver in combination, a rotary type-wheel shaft having a type wheel slidably mounted thereon, type-wheel positioning mechanism comprising a transmitting circuit for controlling the rotation of said shaft, means for holding a sheet of paper, a movable printing platen 5 adapted to press said sheet against said type wheel for printing, letter spacing mechanism comprising a vibrating member adapted in one movement to shift said type-wheel along its shaft transversely of said paper sheet and in its return movement to operate said printing platen, an electro-magnetic actuator for operating said line spacing mechanism and a relay circuit controlled by said transmitting circuit for energizing said 10 actuator.
15. In a printing telegraph receiver in combination, a rotary type-wheel shaft having a type-wheel slidably mounted thereon, type-wheel positioning mechanism comprising a transmitting circuit for controlling the rotation of said shaft, means for holding a sheet of paper, a movable printing platen adapted to impress said sheet against said type-wheel for printing, letter-spacing 15 mechanism comprising a reciprocating rack arranged to feed said type-wheel along said shaft transversely of said paper sheet in its forward movement and having connections for operating said printing platen in its return movement, an electro-magnetic actuator for moving said rack and a relay circuit controlled by said transmitting circuit for energizing said actuator.
16. In a printing telegraph receiver in 20 combination, a type-wheel carrying a series of type, positioning mechanism for determining the particular type to be printed, means for holding a sheet of paper, printing mechanism for impressing said paper sheet against said type wheel for printing, an actuator for said printing mechanism, line-spacing mechanism for shifting said paper longitudinally of said type-wheel, an electro-magnetic actuator for operating said line-spacing mechanism, an energizing circuit for said electro-magnetic actuator adapted to be closed by the coöperative action of said printing mechanism actuator and said type-wheel positioning mechanism.
17. In a printing telegraph receiver in 25 combination, a type-wheel carrying a series of type, type-wheel positioning mechanism for determining the particular type to be printed, means for holding a sheet of paper, printing mechanism for impressing said paper sheet against said type-wheel for printing, an electro-magnetic actuator for operating said printing mechanism, a relay circuit for energizing said actuator controlled by said transmitting circuit, line-

spacing mechanism for shifting said paper longitudinally of said type-wheel, a second electro-magnetic actuator for operating said line-spacing mechanism, a relay circuit for energizing said second actuator adapted to 70 be closed by the operation of said first-named electro-magnetic actuator when said transmitting circuit has fixed said type-wheel in a predetermined position.

18. In a printing telegraph receiver in 75 combination, a type-wheel shaft carrying a type-wheel, type-wheel positioning mechanism for controlling the rotation of said shaft, means for holding a sheet of paper and printing mechanism for impressing said 80 paper sheet against said type-wheel for printing, an actuator for said printing mechanism, line-spacing mechanism for shifting said paper longitudinally of said type-wheel, an electro-magnetic actuator for 85 operating said line-spacing mechanism, an energizing circuit for said electro-magnetic actuator adapted to be closed by the operation of said printing mechanism actuator when said type-wheel shaft is in a predetermined position.

19. In a printing telegraph receiver in 90 combination, a type-wheel carrying a series of type, type-wheel positioning mechanism comprising a transmitting circuit for determining the particular type to be printed, means for holding a sheet of paper and letter-spacing mechanism for shifting said type-wheel and paper sheet transversely of one another, an actuator for said letter-spacing mechanism, line-spacing mechanism for shifting said paper longitudinally of said type-wheel, an electro-magnetic actuator for operating said line-spacing mechanism and an energizing circuit for said electro-magnetic actuator adapted to be closed by the coöperative action of said letter-spacing actuator and said type-wheel positioning mechanism.

20. In a printing telegraph receiver in 100 combination, a type-wheel carrying a series of type, type-wheel positioning mechanism comprising a transmitting circuit for determining the particular type to be printed, means for holding a sheet of paper and letter-spacing mechanism for shifting said type-wheel and paper sheet transversely of one another, an electro-magnetic actuator for operating said letter-spacing mechanism, a relay circuit controlled by said transmitting circuit for energizing said actuator, line-spacing mechanism for shifting said paper longitudinally of said type-wheel, a second electro-magnetic actuator for operating said line-spacing mechanism, a relay circuit for energizing said actuator adapted to 105 be closed by the operation of said first-named actuator when said transmitting circuit has fixed said type-wheel in a predetermined position.

21. In a printing telegraph receiver in 110

- combination, a type-wheel carrying a series of type, type-wheel positioning mechanism comprising a transmitting circuit for determining the particular type to be printed, means for holding a sheet of paper, letter-spacing mechanism for shifting said type-wheel and paper sheet transversely of one another, printing mechanism for impressing said paper sheet against said type-wheel for printing, a single actuator for operating said letter-spacing and said printing mechanism, line-spacing mechanism for shifting said paper longitudinally of said type-wheel, an electro-magnetic actuator for operating said line-spacing mechanism and an energizing circuit for said electro-magnetic actuator adapted to be closed by the co-operative action of said first-named actuator and said type-wheel positioning mechanism. 5
22. In a printing telegraph receiver in combination, a type-wheel carrying a series of type, type-wheel positioning mechanism comprising a transmitting circuit for determining the particular type to be printed, means for holding a sheet of paper, letter-spacing mechanism for shifting said type-wheel and paper sheet transversely of one another, printing mechanism for impressing said paper sheet against said type-wheel for printing, a single actuator for operating said letter-spacing and said printing mechanism, line-spacing mechanism for shifting said paper longitudinally of said type-wheel, an electro-magnetic actuator for operating said line-spacing mechanism and an energizing circuit for said electro-magnetic actuator adapted to be closed by the operation of said first-named actuator when said transmitting circuit has fixed said type-wheel in a predetermined position. 10
23. In a printing telegraph receiver in combination, a type-wheel carrying a series of type, type-wheel positioning mechanism comprising a transmitting circuit for determining the particular type to be printed, means for holding a sheet of paper, letter-spacing mechanism for shifting said type-wheel and paper sheet transversely of one another comprising an electro-magnetic actuator connected mechanically with said letter-spacing mechanism, a circuit closer controlled by the said actuator, line-spacing mechanism for shifting said paper longitudinally of said type-wheel comprising feed rolls, and pawl and ratchet means for rotating said rolls, an electro-magnetic actuator for operating said pawl and ratchet means, an individual relay circuit controlled by said circuit closer and in which said last named actuator is located, and a relay magnet operatively connected with said relay circuit and controlled by said transmitting circuit, the armature of said relay magnet being in the same circuit as the electro-magnetic of said first named actuator. 15
24. In a printing telegraph receiver in combination, a type-wheel carrying a series of type, type-wheel positioning mechanism for determining the particular type to be printed, means for holding a sheet of paper, letter-spacing mechanism for shifting said type-wheel and paper sheet transversely of one another, line-spacing mechanism for shifting said paper longitudinally of said type-wheel comprising paper feed rolls, pawl and ratchet means for rotating said rolls, and checking devices operated by said pawl means for keeping said feed rolls under control of said pawl and ratchet mechanism at all times. 20
25. In a printing telegraph receiver in combination, a type-wheel carrying a series of type, type-wheel positioning mechanism for determining the particular type to be printed, means for holding a sheet of paper, letter-spacing mechanism for shifting said type-wheel and paper sheet transversely of one another, line-spacing mechanism for shifting said paper longitudinally of said type-wheel comprising paper feed rolls, pawl and ratchet means for rotating said rolls, and checking devices for keeping said feed rolls under control of said pawl and ratchet means at all times, comprising a stop for engaging said feed rolls at each propelling movement of said pawl and ratchet means, and a second stop for preventing the operation of said feed rolls when said pawl and ratchet means are at rest. 25
26. In a printing telegraph receiver in combination, a type-wheel carrying a series of type, type-wheel positioning mechanism comprising a transmitting circuit for determining the particular type to be printed, means for holding a sheet of paper, letter-spacing mechanism for shifting said type-wheel and paper sheet transversely of one another, line-spacing mechanism for shifting said paper longitudinally of said type-wheel comprising paper feeding rolls, pawl and ratchet means for rotating said rolls, and checking devices for keeping said feed rolls under control of said pawl and ratchet mechanism at all times, comprising a stop for engaging said feed rolls at each propelling movement of said pawl and ratchet means, and a second stop for preventing the operation of said feed rolls when said pawl and ratchet means are at rest, an electro-magnetic actuator for operating said pawl and ratchet means and said checking devices, and a relay circuit controlled by said transmitting circuit for energizing said actuator. 30
27. In a printing telegraph receiver in combination, a type-wheel carrying a series of type, type-wheel positioning mechanism for determining the particular type to be printed, means for holding a sheet of paper, letter-spacing mechanism for shifting said 35

type-wheel and paper sheet transversely of one another, comprising a stationary and a reciprocating rack and a pawl carriage having pawls engaging said racks, line-spacing mechanism for shifting said paper longitudinally of said type-wheel, an electro-magnetic actuator for said line-spacing mechanism having a vibrating armature arm arranged to supply its own power to simultaneously operate said line-spacing mechanism and withdraw said carriage pawls from said racks to thereby release said carriage for its return.

28. In a printing telegraph receiver in combination, a type-wheel carrying a series of type, type-wheel positioning mechanism for determining the particular type to be printed, means for holding a sheet of paper and letter-spacing mechanism for shifting said type-wheel and paper sheet transversely of one another, comprising a stationary and a reciprocating feed rack bar and a pawl carriage having pawls engaging said feed racks, means tending to return said carriage at all times, line-spacing mechanism for shifting said paper longitudinally of said type-wheel comprising paper feed rolls with pawl and ratchet means for rotating said rolls, an electro-magnetic actuator for said line-spacing mechanism having a vibrating armature arm arranged to supply its own power to simultaneously operate said pawl and ratchet means and withdraw said carriage pawls from said racks to thereby allow the return of said carriage.

29. In a printing telegraph receiver in combination, a rotary type-wheel shaft carrying a type-wheel slidably mounted thereon, letter-spacing mechanism comprising a stationary and reciprocating feed rack, a carriage for moving said type-wheel along said shaft having pawls engaging said feed racks to be shifted thereby, means tending to return said carriage at all times, line-spacing mechanism for shifting said paper longitudinally of said type-wheel, an electro-magnetic actuator for said line-spacing mechanism having a vibrating armature arm arranged to supply its own power to simultaneously operate said line-spacing mechanism and withdraw said carriage pawls from said racks to thereby allow the return of said carriage.

30. In a printing telegraph receiver in combination, a rotary type-wheel shaft carrying a type-wheel slidably mounted thereon, letter-spacing mechanism comprising a carriage having a yoke for engaging said type-wheel to move the same along said shaft, a plurality of guide supports separate from and parallel with said shaft and on which said carriage has a two-point bearing for preventing it from resting against said type-wheel shaft, means for positively feeding said carriage step by step along its

support in one direction and means tending to return said carriage at all times in the other direction.

31. In a printing telegraph receiver in combination, a rotary type-wheel shaft carrying a type-wheel slidably mounted thereon, letter-spacing mechanism comprising a carriage having a yoke for engaging said type-wheel to shift the same along said shaft, said carriage being slidably supported upon a pair of separated rails so as not to rest against said type-wheel shaft, means for positively feeding said carriage step by step along said rails in one direction, comprising an alternate stationary and reciprocating feed rack and pawls on said carriage for engaging said feed racks, and means tending to return said carriage at all times in the other direction.

32. In a printing telegraph receiver in combination, a rotary type-wheel shaft carrying a type-wheel slidably mounted thereon, said type-wheel being keyed to said shaft for rotation therewith and having a loose play in said key engagement, and tension means tending to rotate said type-wheel relatively to said shaft.

33. In a printing telegraph receiver in combination, a rotary shaft on which are a series of type, mounted slidably on said shaft, said type having a key connection with said shaft for rotation therewith and having a loose play in said key engagement, and means tending to rotate said series of type relatively to said shaft.

34. In a printing telegraph receiver in combination, a rotary type wheel shaft, a type-wheel carrying a series of type and slidably mounted on said shaft, said type-wheel being keyed to said shaft for rotation therewith and having a loose play in said key engagement, means for printing from said type-wheel, and pressure means acting on said wheel to take up said play for registering every type thereof to the same printing point during the printing operation.

35. In a printing telegraph receiver in combination, a rotary type-wheel shaft carrying a type-wheel slidably mounted thereon, said type-wheel being keyed to said shaft for rotation therewith and having a loose play in said key engagement, a type-wheel follower likewise keyed to said shaft with loose play in said key engagement, and a spring connecting said type-wheel and follower tending to rotate them in opposite directions relative to said shaft.

36. In a printing telegraph receiver in combination, a rotary type-wheel shaft carrying a type-wheel, means creating a constant tension on said shaft tending to rotate the same, comprising a coil spring connected thereto, an electro-magnetic actuator having a vibrating armature with connec-

tions for winding up said coil spring, an energizing circuit for said actuator closed by each rotation of said type-wheel shaft.

37. In a printing telegraph receiver in combination, a rotary type-wheel shaft carrying a type-wheel, means creating a constant tension on said shaft tending to rotate the same, comprising a coil spring connected thereto, an electro-magnetic actuator having a vibrating armature with connections for winding up said coil spring, an energizing circuit for said actuator, and means controlled by the rotation of said type-wheel shaft so as to maintain said spring in its wound up condition, said energizing circuit being of insufficient strength to operate said actuator when said spring is fully wound.

38. In a printing telegraph receiver in combination, a rotary type-wheel shaft carrying a type-wheel, means creating a constant tension on said shaft tending to rotate the same, comprising a coil spring positively connected thereto and coiled about and connected with said shaft, an electro-magnetic actuator having a vibrating armature with connections for winding up said coil spring, an energizing circuit for said actuator, and means for controlling said energizing circuit so as to maintain said spring in its wound up condition, said energizing circuit being of insufficient strength to operate said actuator when said spring is fully wound, and escapement means mounted on said type-wheel shaft to release it.

39. In a printing telegraph receiver in combination, a rotary type-wheel shaft carrying a type-wheel, means creating a constant tension on said shaft tending to rotate the same, comprising a coil spring connected thereto, an electro-magnetic actuator having a vibrating armature with connections for winding up said coil spring, an energizing circuit for said actuator, a commutator on said type-wheel shaft in said energizing circuit adapted to make and break the circuit during the rotation of said shaft to thereby maintain said spring in its wound up condition, said energizing circuit being of insufficient strength to operate said actuator when said spring is fully wound.

40. In a printing telegraph receiver in combination, a rotary type-wheel carrying a series of type, means for holding a sheet of paper and a printing platen for impressing said paper against said type-wheel, a guard plate covering the periphery of said type-wheel adjacent the printing point, and having a transverse slot therein wide enough to expose the type, the ends of said slot being cut away so as not to contact with said paper sheet.

41. In a printing telegraph receiver in combination, a rotary type-wheel shaft, and means for creating a constant tension on

said shaft tending to rotate the same comprising a coiled torsion spring wound around said shaft having polysided coils of angular contour, the sides of said coil being substantially equal length and the angular parts of said coils being separated therefore from said shaft.

42. In a printing telegraph receiver in combination, letter-spacing mechanism comprising a reciprocating feed rack, a pawl-carriage having a pawl engaged by said rack, a checking bar located above said pawl to prevent the overthrow of said pawl-carriage.

43. In a printing telegraph receiver in combination, letter-spacing mechanism comprising alternate stationary and reciprocating feed racks, a pawl-carriage having pawls engaged by said racks, and a toothed checking bar located above one of said bars to prevent the over-throw of said pawl-carriage under the impulse of said reciprocating rack.

44. In a printing telegraph receiver in combination, a type-wheel and paper-carriage movable transversely of one another for letter spacing, means for feeding said type-wheel step by step transversely of said paper-carriage, and checking means for positively limiting each forward movement of said type-wheel to accurately space said printed characters.

45. In a printing telegraph receiver in combination, a letter-spacing mechanism comprising alternate stationary and reciprocating feed racks, a pawl-carriage having pawls engaged by said racks, and a checking bar located above said pawls provided with depending teeth, one of said pawls having a projection for engaging the teeth of said checking bar when advanced.

46. In a printing telegraph receiver in combination, a letter-spacing mechanism comprising alternate stationary and reciprocating feed racks, a pawl-carriage having pawls engaged by said racks, and a checking bar located above said pawls provided with depending teeth oppositely disposed to the teeth of said stationary rack bar and set slightly in advance of the same, one of said pawls having a projection for engaging the teeth of said checking bar when advanced.

47. In a printing telegraph receiver, the combination of paper holding means, a movable type-wheel, actuating means therefor, a magnet for storing power in said actuating means for rotating said type-wheel, letter-spacing mechanism, a magnet for actuating said spacing mechanism, a magnet operable to change the relative positions of said type-wheel and the paper for line spacing, energizing circuits for each of said magnets, a relay magnet controlling said circuits, a magnet for controlling the rotation of said type-wheel by the said actuating means, and transmission means for energizing the said

controlling magnet, and for actuating said relay by a prolonged pulse through said controlling magnet when the type of the type-wheel is properly positioned.

5 48. In a printing telegraph receiver, the combination of paper holding means, a movable type-wheel, actuating means therefor, a magnet for storing power in said actuating means for rotating said type-wheel, letter-spacing mechanism, impression means, a magnet for actuating said spacing mechanism and said impression means, a magnet operable to change the relative positions of said type-wheel and the paper for line spacing, energizing circuits for each of said magnets, a relay magnet controlling said circuits, a magnet for controlling the rotation of said type-wheel by the said actuating means, and transmission means for energizing the said controlling magnet, and for actuating said relay by a prolonged pulse through said controlling magnet when the type of the type-wheel is properly positioned.

25 49. In a printing telegraph receiver, the combination of paper holding means, a movable type-wheel, actuating means therefor, a magnet for storing power in said actuating means for rotating said type-wheel, letter-spacing mechanism, means for actuating said spacing mechanism, a magnet operable to change the relative positions of said type-wheel and the paper for line-spacing, energizing circuits for each of said magnets, a relay magnet controlling said circuits, a magnet for controlling the rotation of said type-wheel by the said actuating means, and transmission means for energizing the

said controlling magnet, and for actuating said relay by a prolonged pulse through said controlling magnet when the type of the type-wheel is properly positioned.

50. In a printing telegraph receiver, the combination of paper holding means, a movable type-wheel, actuating means therefor, a magnet for storing power in said actuating means for rotating said type-wheel, letter-spacing mechanism, a magnet for actuating said spacing mechanism, means operable to change the relative positions of said type-wheel and the paper for line-spacing, energizing circuits for each of said magnets, a relay magnet controlling said circuits, a magnet for controlling the rotation of said type-wheel by the said actuating means, and transmission means for energizing the said controlling magnet, and for actuating said relay by a prolonged pulse through said controlling magnet when the type of the type-wheel is properly positioned.

51. In a printing telegraph receiver, the combination of a rotary cylindrical type-shaft, and means for creating a constant tension on said shaft tending to rotate the same comprising a torsion spring coiled loosely about said shaft and having poly-sided coils of angular contour, the sides of said coils being of substantially equal length.

Signed at New York city, New York, this 31st day of August, 1911.
